[57] **CLAIM**

The ornamental design for a pool table, as shown and described.

DESCRIPTION

FIG. 1 is a top plan view of a pool table showing my new design;

FIG. 2 is a left side elevational view thereof; the right side elevational view being a mirror image thereof;

FIG. 3 is a front elevational view thereof; the rear elevational view being a mirror image thereof;

FIG. 4 is a left side elevational view of a second embodiment of the pool table; the right side elevational view being a mirror image thereof; and,

FIG. 5 is a front elevational view of the pool table of FIG. 4, the rear elevational view being a mirror image thereof.

The bottom is disclaimed. The top plan view of the second embodiment shown in FIG. 4 is the same as shown in FIG. 1.
